CLAIM

The ornamental design for a front panel for bullet proof vest, as shown.

DESCRIPTION

FIG. 1 is a top, front, and right side perspective view for a front panel for bullet proof vest showing our new design; FIG. 2 is a bottom, rear, and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.
